US0D1001152S

(12) **United States Design Patent** (10) **Patent No.:** **US D1,001,152 S**
Kumar et al. (45) **Date of Patent:** **** Oct. 10, 2023**

(54) **DISPLAY SCREEN OR PORTION THEREOF WITH GRAPHICAL USER INTERFACE**

(71) Applicant: **ABBOTT DIABETES CARE INC.**,
 Alameda, CA (US)

(72) Inventors: **Panganamala Ashwin Kumar**,
 Oakland, CA (US); **Joel Goldsmith**,
 Oakland, CA (US)

(73) Assignee: **ABBOTT DIABETES CARE INC.**,
 Alameda, CA (US)

(**) Term: **15 Years**

(21) Appl. No.: **29/798,143**

(22) Filed: **Jul. 6, 2021**

Related U.S. Application Data

(63) Continuation of application No. 16/267,591, filed on Feb. 5, 2019, now abandoned.

(57) **CLAIM**

The ornamental design for a display screen or portion thereof with graphical user interface, as shown and described.

DESCRIPTION

FIG. 1 is a front view of a display screen or portion thereof with graphical user interface showing our new design according to a first embodiment; and,

FIG. 2 is a front view of a display screen or portion thereof with graphical user interface showing our new design according to a second embodiment.

The outer perimeter illustrated by dashed broken lines in the drawings illustrates a display screen or portion thereof and forms no part of the claimed design. The remaining broken lines illustrate portions of the graphical user interface that form no part of the claim design.
